Primary Examiner—Ruth McInroy**Attorney, Agent, or Firm**—George A. Bode**[57]****CLAIM**

The ornamental design for an eye covering, as shown and described.

DESCRIPTION

FIG. 1 is a right side perspective view of an eye covering showing my new design, the head shown in broken lines is for illustrative purposes only and forms no part of the claimed design;

FIG. 2 is an enlarged right side elevational view thereof, the opposite side being a mirror image;

FIG. 3 is an enlarged front elevational view thereof;

FIG. 4 is an enlarged top plan view thereof;

FIG. 5 is an enlarged bottom plan view thereof; and,

FIG. 6 is an enlarged rear elevational view thereof.

FIG. 1FIG. 2FIG. 3FIG. 4FIG. 5FIG. 6
